LORENZO J. STANNARD AND MARTIN L. PERRY, OF NEWARK, NEW YORK.

Letters Patent No. 88,093, dated March 23, 1869.

IMPROVEMENT IN APPARATUS FOR TURNING LOGS.

The Schedule referred to in these Letters Patent and making part of the same.

To all whom it may concern:

Be it known that we, LORENZO J. STANNARD and MARTIN L. PERRY, of Newark, in the county of Tioga, and State of New York, have invented a new and useful Machine for Turning, or Handling Logs in Saw-Mills; and we do hereby declare the following to be a full, clear, and exact description of the same, reference being had to the annexed drawings, and to the letters of reference marked thereon.

The nature of our invention consists in placing in the upper part of saw-mills, to be out of the way, and immediately above the logs to be sawed, a shaft, with a drum, or cylinder thereon, and so operating the shaft, that a chain or rope wound upon the cylinder, shall be made to descend, and when attached to the log or timber to be turned upon the head-blocks, that the chain is drawn up, the log turned and lowered on a flat side, as slowly or carefully as the attendant may desire.

To enable others to make and use our invention, we will describe its construction and operation.

Sufficiently high to be out of the way, and above the log-carriage, is a shaft, on which is a drum, or cylinder, A; also a large friction-wheel, B.

On the cylinder is a chain or rope, with a hook at the end, the chain being of sufficient length to extend to the log below it.

Motion is given to the cylinder by the small friction-wheel D on the shaft C, the wheel D being pressed upon the wheel B by the lever L.

The shaft C has a pulley, E, from which a belt runs to any shaft in the mill from which power may be conveniently obtained.

The shaft C is also provided with a small pulley, F, from which a belt runs to pulley H on shaft G.

This shaft has a friction-wheel, J, which also comes in contact with the large friction-wheel on the cylinder-shaft, and is held against it or moved back by the lever K.

The operation of the machine is as follows:

Motion being communicated to pulley E, the shaft C is left constantly moving while the mill is running. The lever L being released, and lever K moved up, the friction-wheel J turns the cylinder A, and unwinds the chain, and the hook descends to the log, and is fastened thereto, when lever K is pushed back, and the friction-wheel D brought in contact, when the chain is drawn slowly up, and the hook being attached to the log, turns it over.

When square timber is turned, which would fall heavily on a flat side, the hook prevents it from falling, and it is lowered carefully by means of the brake O, acting on the periphery of the wheel B.

What we claim as our invention, and desire to secure by Letters Patent, is—

The arrangement of the shafts A, C, and G, with their friction-wheels and pulleys, in combination with the levers K, L, and brake O, the whole constructed and operating substantially in the manner herein set forth.

LORENZO J. STANNARD.
MARTIN L. PERRY.
